UNITED STATES PATENT OFFICE.

GEORGE E. GREENLEAF, OF PLAINFIELD, NEW JERSEY, ASSIGNOR TO NILES-BEMENT-POND COMPANY, OF NEW YORK, N. Y., A CORPORATION OF NEW JERSEY.

HEADSTOCK-BEARING FOR LATHES.

1,345,671.

Specification of Letters Patent.

Patented July 6, 1920.

Application filed November 9, 1918. Serial No. 261,781.

To all whom it may concern:

Be it known that I, GEORGE E. GREENLEAF, a citizen of the United States, residing at Plainfield, in the county of Union and State of New Jersey, have invented certain new and useful Improvements in Headstock-Bearings for Lathes, of which the following is a specification.

The object of the invention is to provide an improved bearing for the inner end of the main work spindle of a lathe headstock whereby the spindle may be raised or lowered either for preliminary adjustment or to compensate for wear.

15 In the accompanying drawing, which shows the preferred embodiment of the invention,

Figure 1 is a front elevation, with parts broken away and shown in section, of a lathe headstock having a bearing embodying my invention.

Fig. 2 is an end view of the headstock, the face plate being removed and a part of the adjusting means being shown in section.

25 Fig. 3 is a fragmentary view similar to Fig. 2 but showing the bearing details on an enlarged scale.

Referring to the drawing, the lathe headstock comprises lower and upper frame sections 1 and 2 which are secured together in any usual or preferred manner. The main work spindle is indicated at 3 and is arranged horizontally. It is supported in two bearings 4 and 5 which are carried on the frame preferably on the lower section thereof. Also carried by the frame is suitable gearing 6 for driving the spindle. As illustrated, the lathe is driven by an electric motor 7 which is connected with the gearing 6. Preferably the frame sections 1 and 2 are so constructed as to constitute a casting which incloses the major portions of the drive gearing and of the spindle 3. The details of the drive gearing and of the frame or casing can be varied widely but that which I have shown for purposes of illustration is similar to that presented in the copending application of George E. Greenleaf and Clifford F. Randolph for lathe headstocks, Serial No. 261,780, filed November 9, 1918.

The bearing 5 comprises upper and lower brasses 8 and 9 which directly engage the journal part of the spindle. These brasses

are mounted in a recess which is formed partly in the lower section 1 of the frame and partly in a cap 10 bolted to the lower section. The sides of the lower brass 9 are vertical and engage vertical guides formed 60 at the sides of the bearing recess.

The bottom of the brass 9 is inclined at 11 and a wedge block 12 is interposed between the inclined bottom 11 of the brass and the horizontal bottom 13 of the recess. 65 The frame section 1 is provided at the rear with a horizontal aperture 14 adjacent the rear end of the wedge block 12. The front or inner part of the aperture 14 is threaded at 15 and a hollow bolt 16 fits the threaded part of the aperture and at its front end engages the rear end of the wedge block 12. A bolt 17 extends through the aperture in the bolt 16 and is threaded into an aperture in the wedge block 12. 70

By means of the two threaded bolts 16 and 17, the wedge block can be moved positively in either direction. If the wedge block is to be moved toward the rear to raise the brass 9, both of the bolts 16 and 17 are 80 first loosened, the bolt 16 being turned only to a slight extent, the exact amount of movement being determined by the desired amount of movement of the wedge block. Then the bolt 17 is turned in the other direction. The head of the bolt 17 abuts against the head of the bolt 16 and thus enables the bolt 17 to positively draw the wedge block 12 rearward until it engages the front end of the bolt 16. When the wedge block 90 is to be moved toward the front, the bolt 17 is first loosened and then the bolt 16 is turned until the wedge block has been moved to the desired extent. After that the bolt 17 is tightened, thus locking the wedge 95 block in adjusted position. It will be observed that after either adjustment the block is directly engaged by both bolts, being thus firmly locked in position. The two bolts engage each other and thus frictionally hold 100 each other against turning.

Oil is supplied to the bearing through a hole 18 and oil is permitted to flow from the bearing through a hole 19 in the bottom brass 9. The hole 19 registers with a hole 20 in the wedge block 12, this hole 20 being elongated to permit movement of the block without moving the hole out of register. From the hole 20 the oil discharges into a drain passage 21.

The adjusting means that I have described can be used at the initial construction or assembling of the lathe to properly align the work spindle. Its principal usefulness, however, is to compensate for the wear which occurs after the lathe has been used. When heavy pieces of work are turned, considerable weight is thrown on the bearing 5 with the result that the lower 10 brass thereof wears relatively rapidly. Even a small amount of wear will throw the spindle out of alignment and thus interfere with the accuracy of the lathe. With a lathe headstock embodying my invention the 15 inner spindle bearing can be taken up from time to time as wear takes place, the spindle being thus maintained in correct alignment at all times.

What I claim is:

- 20 1. In a lathe headstock, the combination of a box-like frame, a horizontal work spindle, drive gearing for the spindle inclosed within the frame, bearings provided at the respective ends of the frame, the work 25 spindle being mounted in such bearings, passing through the frame and projecting outside thereof at one end, a lathe face plate mounted on such projecting end, the bearing adjacent the face plate including an upper brass and a lower brass provided with a plane wedge-engaging bottom, a wedge block under the lower brass and engaging the bottom thereof, and screw means engaging the wedge block and extending through 30 the frame to the outside whereby the wedge block may be positively moved in either direction to raise or lower the work spindle and face plate to compensate for wear.
- 35 2. In a lathe headstock, the combination 40 of a box-like frame, a horizontal work spindle, drive gearing for the spindle inclosed within the frame, bearings provided at the respective ends of the frame, the work spindle being mounted in such bearings,

passing through the frame and projecting 45 outside thereof at one end, a lathe face plate mounted on such projecting end, the bearing adjacent the face plate including an upper brass and a lower brass each provided with a hole therein for the passage of the 50 bearing lubricant therethrough and the lower brass being provided with a plane wedge-engaging bottom, a wedge block engaging the bottom of the lower brass and provided with an elongated hole registering 55 with the hole in the lower brass whereby the bearing lubricant is drained from the bearing, and screw means engaging the wedge block and extending through the frame to the outside whereby the wedge 60 block may be moved in either direction to raise or lower the work spindle and face plate to compensate for wear.

3. In a lathe headstock, the combination of a frame comprising an upper section and a lower section, a horizontal work spindle, drive gearing for the spindle inclosed within the frame, bearings provided at the respective ends of the frame and supported on the lower section independently of the 65 upper section, the work spindle being mounted in such bearings, passing through the frame and projecting outside thereof at one end, a lathe face plate mounted on such projecting end, the bearing adjacent the face 70 plate including an upper brass and a lower brass, a wedge block under the lower brass and engaging the bottom thereof, and screw means engaging the wedge block and extending through the frame to the outside 75 whereby the wedge block may be moved in either direction to raise or lower the work spindle and face plate to compensate for wear.

In testimony whereof I hereto affix my 85 signature.

GEORGE E. GREENLEAF.
